Primary Examiner — Sanjeev Paul*Assistant Examiner* — Breana Copeland(74) *Attorney, Agent, or Firm* — Jose Cherson Weissbrot(57) **CLAIM**

The ornamental design for a ice silk eye mask, as shown and described.

DESCRIPTION

FIG. 1 is a perspective view of a ice silk eye mask showing my new design;

FIG. 2 is another perspective view thereof;

FIG. 3 is a front elevational view thereof;

FIG. 4 is a rear elevational view thereof;

FIG. 5 is a left side view thereof;

FIG. 6 is a right side view thereof;

FIG. 7 is a top plan view thereof;

FIG. 8 is a bottom plan view thereof; and,

FIG. 9 is a partial enlarged view of FIG. 1.

The broken lines in the figures are for the purposes of illustrating portions of the ice silk eye mask, which form no part of the claimed design.
